UNITED STATES PATENT OFFICE.

GABRIEL J. VIRGILE, OF BROOKLYN, NEW YORK, ASSIGNOR TO CHENEY BROTHERS, OF SOUTH MANCHESTER, CONNECTICUT, A CORPORATION OF CONNECTICUT.

DESIGN FOR A TEXTILE FABRIC.

Application filed May 29, 1928. Serial No. 26,906. Term of patent 14 years.

To all whom it may concern:

Be it known that I, GABRIEL J. VIRGILE, a citizen of the United States, residing at 60 Clarkson Avenue, borough of Brooklyn, county of Kings, State of New York, have invented a new, original, and ornamental Design for a Textile Fabric, of which the following is a specification, reference being had to the accompanying drawing, forming part thereof.

The figure is a representation of a textile fabric showing my new design.

I claim: The ornamental design for a textile fabric as shown.

GABRIEL J. VIRGILE.
